CLAIM

The ornamental design for a game ball, as shown and described.

DESCRIPTION

FIG. 1 is a front elevational view of the game ball showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an enlarged detailed view of a fragment of the game ball shown in FIG. 6 showing the fingertip-receiving-depressions in the surface of the game ball.

In FIGS. 1-6, the circles represent fingertip-receiving-depressions in the surface of the game ball, an enlargement of which is depicted in FIG. 7.
